UNITED STATES PATENT OFFICE

102,092

DESIGN FOR AN ICE CREAM CONE

Harold Payne, Cincinnati, Ohio, assignor to Premier Cone Baking Company, Cincinnati, Ohio, a corporation of Ohio

Application July 29, 1936, Serial No. 64,117

Term of patent 7 years

To all whom it may concern:

Be it known that I, Harold Payne, a citizen of the United States of America and a resident of Cincinnati, in the county of Hamilton and State of Ohio, have invented a new, original, and ornamental Design for an Ice Cream Cone, of which the following is a specification, reference being made to the accompanying drawing, forming a part thereof.

Fig. 1 is an elevational view of the ice cream cone, showing my new design.

Fig. 2 is a top plan view of the ice cream cone shown in Fig. 1.

I claim:

The ornamental design for an ice cream cone, as shown.

HAROLD PAYNE.
